UNITED STATES PATENT OFFICE

CHARLES S. BUSHNELL, OF ROCHESTER, NEW YORK, ASSIGNOR TO GENERAL RAILWAY SIGNAL COMPANY, OF ROCHESTER, NEW YORK

TRAIN-CONTROL SYSTEM

Application filed March 1, 1927. Serial No. 171,820.

This invention relates in general to train control systems of the intermittent inductive alternating current type, and has more particular reference to a system in which there is an acknowledging whistle and which has an improved acknowledging and reset means. 5

It is desirable, in systems of the character in question, to have acknowledging and reset means so protected that they cannot be interchangeably used to perform each other's functions and it is desirable in connection with these means, to have an acknowledging whistle as well as other audible or visible means, for checking the proper operation of 15 the entire system, and for advising the engineer when it is safe to release the acknowledging contactor.

With the above and other objects in view, it is proposed, in accordance with this invention, to provide an automatic train control system of the kind referred to, which satisfactorily attains the various objects enumerated above.

Further objects, purposes, and characteristic features of the invention will appear as the description thereof progresses, reference being had to the accompanying drawings, showing, solely by way of example, one physical form which the invention may assume. 25 In the drawings:

Fig. 1 represents in a wholly schematic manner, one embodiment of the present invention.

Fig. 2 shows, schematically, trackway control means.

Referring to Figure 1 of the drawing, there is shown a track comprising rails 1, divided, in the usual manner, into electrically insulated blocks by means of insulating joints 2, with a wayside signal 3 at the entrance to each block. The signals, as shown, are of the semaphore type, but could equally well be of any other type, such as color light, or position light signals. As shown in a diagrammatic manner, (Fig. 2) each signal 3 controls an adjacent inductor 4 positioned at the side of the track, by arm 3¹ open and close circuiting inductance coils 4¹ and a condenser 4¹¹, the control being such that the 30 inductor is in an active condition, i. e., coils

4¹ and condenser 4¹¹ open circuited, when the signal is set at danger or caution while it is in an inactive condition, i. e., coils 4¹ and condenser 4¹¹ close circuited, with the signal set at clear. This is accomplished by means 55 of circuits controlled by the signals as shown and including therein the inductance coils 4¹ and condenser 4¹¹, it having been deemed unnecessary to illustrate and describe this control in further detail, since it is not essential for a complete understanding of the present invention.

Carried on the car which is represented conventionally by means of axles and wheels 5, is a receiver 6, shown in the form of an $\mathbb{H}$, 65 but which might readily be of any other suitable design. Carried on the receiver 6 are two primary coils P, connected in series with each other and with a condenser 7, and a source of alternating current 8, shown as an alternator. The characteristics of the circuit including the primary coils are such as to tune this circuit to oscillate most freely at the frequency of the alternating current supplied by the alternator 8, which frequency is 70 preferably relatively high, as of the order of about 360 cycles per second, for instance.

Also carried on the receiver 6 are two secondary coils S, which are connected in series with each other and with a condenser 9 and coils 10 of a main relay MR, in a circuit which is obvious from the drawing. As in the case of the primary coils, the circuit containing the secondary coils is tuned to oscillate most freely at the frequency of the alternating current supplied by the alternator 8. 75

The structure so far described operates in the following manner. When the receiver 6 passes over an inductor 4, without touching it as is usual in inductive train control systems, as is well understood by those skilled in this particular art, if the inductor 4 be in its active condition, it will so effect the flux distribution in the receiver 6 as to reduce the induced current flowing in the secondary coils S, to zero, or at least sufficiently, depending upon the air gap between the inductor and receiver, to de-energize the coils 10 of the main relay MR. On the other hand, if the particular wayside signal in question 100

be set at clear, the inductor is then in its inactive condition, as explained above, and has no effect whatever on the receiver, or else has the effect of actually increasing the amount of current flowing through the secondary coils S so that under such conditions, the relay MR is operatively unaffected.

The particular manner in which the flux distribution in the receiver is controlled by the inductor is not explained in detail, as it is quite unnecessary for a complete understanding of the present invention.

The relay MR has its coils 10 on a magnetic core 11 which is preferably a laminated structure, in order to cut down eddy current losses and the like, and has a pivoted armature 12, normally held in the attracted position shown, by means of the core 11, and biased in a clockwise direction, to move when said coils are deenergized, by means of a spring 13. Carried by the armature 12, are armature contacts 14 and 15, electrically insulated from the body of the armature by insulating joints 16.

Associated with the relay MR is a restoring relay RR, very similar to relay MR, but unlike MR, its energizing circuit is not tuned, and comprising coils 17 carried on a laminated core 18, together with a pivoted armature 19 biased in a clockwise direction by a spring 20 and carrying an armature contact 21 insulated from the body of the armature by means of an insulating joint 16. The armature 19 is arranged to have a retarded drop-away, due for example to its connection, by means of a rod 22, to a dash pot 23. At the end of the armature 19, opposite to the contact 21, is an upwardly projected restoring pin 24, positioned in the path of rotation of armature 12 of relay MR, for a purpose to be described below.

The system shown includes a device EPV, which may be an electro-pneumatic valve, arranged to be normally energized, and when de-energized to either initiate an automatic application of the brakes, or impose a minimum speed limit, or a gradually decreasing tapered speed limit, on the train, or to in any other desired manner impose a restrictive influence on the movement of the train. The EPV has a contact member 25 which is held up when the device is energized, and drops away upon de-energization thereof.

A reset device Res is included, comprising a manually operable rod 26 connected to contact finger 27, normally open, and 28, normally closed, for simultaneously moving such contact fingers to their reverse positions. This reset device is positioned so to be inaccessible for operation while the train is in motion, as for example, by having it accessible only from the ground, whereby to prevent misuse of the device.

An acknowledging device, Ack included in the system, comprises a manually depressible

rod 29, biased to an upward position by a spring 30, and carrying pins 31 and 32 for respectively controlling movable contact fingers 33 and 34. On depression of the rod 29 the contact 33 is moved to its lower position, by pin 31, while pin 32 releases contact finger 34 and permits a spring 35 to move finger 34 downwardly with a retarded action due to dash pot 36, so that finger 34 and its spring 34¹ do not break contact until the lapse of a predetermined time interval after depression of the rod 29, in the present instance preferably about 15 seconds.

There is also included in the system an audible signal, shown as a whistle valve WV, which is connected up to be energized at the proper time to furnish the proper indication.

In order to simplify the wiring diagram and the explanation, letters B and C have been used to indicate the positive and negative terminals of a source of energy such as a storage battery, generator, or the like, and while such source is here contemplated to be a direct current source of energy, obviously alternating current might under certain circumstances be equally well employed. In a like manner, while the relay MR has been shown and described as energized by alternating current, it is likewise obvious that under certain circumstances, direct current could equally well be used.

The restoring relay RR is energized through a circuit beginning at a source C and including the two relay coils 17 in series, contact finger 14 and front contact of relay MR, contact finger and front contacts 25 of EPV, to a source B. Thus its energization requires that the armature of the main relay MR be in energized position, and that the EPV be energized.

On a consideration of the structure described above, and of the energizing circuit just traced for relay RR, it will be seen that upon de-energization of relay MR, its armature 12 will be rocked in a clockwise direction, and thus break the energizing circuit for relay RR. This permits spring 20 to rock armature 19 of relay RR in a clockwise direction, against the action of dash-pot 23, to thereby force the pin 24 against armature 12 thus to restore armature 12 to energized position. Restoration of armature 12 to energized position completes the energizing circuit for relay RR, provided EPV has not, in the meantime become de-energized to drop contact finger 25, and thus the armature 19 of relay RR is drawn back to its attracted position shown in the drawing. In other words, drop-away of relay MR causes drop-away of relay RR, and drop away of relay RR restores the armature 12 of MR, and this in turn, under certain conditions, namely that EPV has remained energized, operates to restore the armature 19 of relay RR to its attracted position.

Furthermore, in the operation above considered, when armature 12 of relay MR is retracted, a circuit is completed for energizing the whistle valve WV through a circuit beginning with a source C, the whistle valve, contact finger 14 and back contact of armature 12, wire 37, contact finger and front contacts 25 of EPV to a source B. The energization, therefore, of the whistle valve WV, requires that relay MR be retracted and that at the same time EPV be energized.

On retraction of either of the two armatures 12 or 19, or both of them, of the interlocked relays MR and RR, the normal energizing circuit for EPV is broken with the result that a brake application, for example, is incurred, and the stick contact 25 of EPV drops away. The normal energizing circuit referred to for EPV includes a source C, the EPV, contact finger and front contact 28 of reset device Res, contact finger and front contacts 15 of armature 12, contact finger and front contacts 21 of armature 19, to a source B. In other words, the normal energizing circuit for EPV requires that the two armatures 12 and 19 be in their attracted positions and that the reset device be in its normal raised position as shown.

When operated, under certain restrictions, the acknowledging device *Ack* operates to forestall an automatic brake application, by preventing de-energization of EPV even though the relays MR and RR drop away. This auxiliary acknowledging circuit for energizing EPV, is a stick circuit including a source of energy B, stick contact and front contacts 25 of EPV, contact finger and front contact 34 and contact finger and back contact 33 of *Ack*, the EPV, to a source C. It will be noted that this energizing circuit can be maintained for only a limited time, since approximately 15 seconds from the time the contact finger 33 makes contact, contact finger 34 breaks contact, and since these two contact fingers are in series in the circuit in question such circuit can be maintained for only approximately 15 seconds. It is therefore necessary, in order to forestall a brake application on passing a signal set at danger or caution, to operate the acknowledging contactor *Ack* shortly before reaching the signal in question, and to release it within a period of 15 seconds. If the acknowledging contactor be tied down, the acknowledging circuit will be broken after 15 seconds, at the finger 34, and the train will be subjected to a brake application upon passing and an active inductor.

Assume, for the purpose of illustration, that the train passes a signal set at clear, in which circumstances the inductor 4 is inactive and has no influence on the receiver 6, so that all the parts remain in the positions shown in the drawing. In these circumstances the EPV remains energized and no brake application is incurred.

Assume now that the train passes an inductor in active condition, that is, with the signal at stop or caution. In these circumstances, assuming that no forestalling action is taken by the engineman, the relay MR is deprived of current so that its armature 12 is retracted, thus breaking the energizing circuit for relay RR at contact finger and front contact 14, and the energizing circuit for EPV at contact finger and front contacts 15, with the result that a brake application is incurred, and the stick contact 25 drops away. Also armature 19 of relay RR drops away, thus permitting pin 24 to restore the armature of relay MR to its attracted position in which it is held by current flowing through the secondary windings 8 since by this time the receiver has passed the inductor.

The restoration of armature 12 does not however, complete the energizing circuit for relay RR since this circuit is broken at the contacts 25, due to de-energization of EPV. Likewise the energizing circuit for the whistle valve WV is broken at the stick contacts 25 before it is completed at the contact finger 14 and its back contact, so that this signal is not energized and does not sound.

Under these circumstances, the train cannot proceed until the brakes are released, and the brakes cannot be released until EPV is re-energized. The acknowledging contactor *Ack* is powerless to re-energize EPV since the acknowledging circuit is broken at the contacts 25 and the only manner in which the normal energizing circuit for EPV can be completed is by energizing relay RR and this can be done only by operation of the reset device Res which is inaccessible while the vehicle is in motion. Accordingly after incurring an automatic brake application, the car must be brought to a stop, after which the engineman can operate the reset device to thereby complete an energizing circuit for relay RR, said circuit including a source B, contact finger and back contact 27, coils 17 of relay RR, to a source C.

On restoring the reset device to its normal position the energizing circuit just described is broken at contact finger 27, by releasing Res, but due to the slow drop-away characteristics of its armature 19, relay RR remains in picked-up position until the normal energizing circuit for EPV is completed through contact finger and front contact 28, and the normal energizing circuit for RR is completed through contact finger and front contacts 25 of EPV, thus restoring all parts to their shown normal positions. When armature 19 is once up, even though the relay RR then be de-energized, the dash-pot device 23 maintains this armature 19 in position to close contacts 21 for a period of time at least equal to the time required for closing reset contact 28 after release of Res, plus the period of time required for closing contacts 25 of

EPV, after EPV has been re-energized through the circuit including the reset contact finger 28.

In the operation described above, had the 5 engineman depressed the acknowledging contactor *Ack* just before passing the active inductor, energy would have been put on EPV through the acknowledging circuit traced above, and thus stick contact 25 would 10 have remained up. In such circumstances, relay MR would have dropped away to de-energize relay RR to thus break the normal energizing circuit for EPV. Armature 19 of relay RR would then have restored relay 15 MR to attracted position, which in turn would then have completed the energizing circuit for relay RR at contact finger and front contact 14, it being remembered that due to the acknowledging circuit, the stick contact 25 20 of EPV remained up.

During the operation just described the whistle valve WV had its energizing circuit completed through contact finger 14 and its back contact, and this circuit remained 25 completed during the time that the slow drop-away armature 19 of relay RR was dropping away. In other words, the duration of the sounding of the whistle valve depends on the time required for armature 19 to drop away 30 sufficiently to restore the armature of relay MR to attracted position, and if it were not for the slow drop away feature of relay RR the whistle valve WV would give but a very short whistle, or possibly none at all.

35 The sounding of the whistle WV checks the operation of the entire system and apprises the engineman that an active inductor is being passed, and upon the audible signal becoming silent, the engineman knows that he can safely release the acknowledging contact or *Ack*, 40 since he has been advised thereby that he is safely past the active inductor.

If acknowledging were accomplished as is sometimes done by putting auxiliary energy 45 on the main relay to hold it up, the above described operation of the whistle valve could not take place and its desirable features would be lost.

With the structure and arrangement of 50 parts described above, it is seen that the acknowledging and the reset devices are safeguarded against misuse and that, with the interlocked relays MR and RR, the restoration of relay MR to attracted position cannot operate to re-energize relay RR if, in the meantime, EPV has been de-energized, due to the 55 fact that the energizing circuit for relay RR passes through contact finger and front contacts 25 of EPV. This stick feature of the 60 EPV permits drop-away and restoring of the main relay armature to give the above described whistle signal without, at the same time, re-energizing EPV. Thus the very desirable feature of retention of the acknowledging 65 whistle is obtained in conjunction with

all the necessary safeguards against misuse of reset and acknowledging devices in connection with this type of automatic train control.

The above rather specific description of one form of this invention has been given solely 70 by way of example, and is not intended, in any manner whatsoever, in a limiting sense. Obviously, the invention can assume many different physical forms, and is susceptible of numerous modifications, and all such forms 75 and modifications, are intended to be covered by this invention, as come within the scope of the appended claims.

Having described my invention I now claim:—

1. In an automatic train control system, a normally energized traffic responsive device, a normally energized restoring member therefor, operating when de-energized to physically restore said device, a normally 85 energized brake applying device acting when de-energized to produce a brake application, and a normal energizing circuit for the brake applying device directly broken upon de-energization of either the traffic responsive 90 device or the restoring member.

2. In an automatic train control system, a normally energized traffic responsive device, a normally energized restoring member therefor, for mechanically acting on said traffic responsive device, a normally energized brake applying device acting when de-energized to produce a brake application, a normal energizing circuit for the brake applying device directly broken upon de-energization of either the traffic responsive device or the restoring member, and a normal energizing circuit for the restoring member broken upon de-energization of the traffic responsive device. 95

3. In an automatic train control system, a traffic responsive device, normally energized to attracted position, a normally energized restoring member therefor, a normally energized brake applying device acting when de-energized to produce a brake application, a normal energizing circuit for the brake applying device directly broken upon de-energization of either the traffic responsive device or the restoring member, a normal 110 energizing circuit for the restoring member broken upon de-energization of the traffic responsive device, and means operative upon de-energization of the restoring member to mechanically move the traffic responsive device to attracted position. 115

4. In an automatic train control system, a normally energized traffic responsive device, a normally energized restoring member therefor, a normally energized brake applying device acting when de-energized to produce a brake application, a normal energizing circuit for the brake applying device directly broken upon de-energization of either the traffic responsive device or the re- 125

storing member, a normal energizing circuit for the restoring member broken upon de-energization of the traffic responsive device, and means, including a front contact of the 5 brake applying device, for completing a temporary energizing circuit for such brake applying device independent of the restoring member and the traffic responsive device.

5. In an automatic train control system, a traffic responsive device normally energized to attracted position, a normally energized restoring member therefor, a normally energized brake applying device acting when de-energized to produce a brake application, 10 a normal energizing circuit for the brake applying device directly broken upon de-energization of either the traffic responsive device or the restoring member, a normal energizing circuit for the restoring member broken upon de-energization of the traffic 15 responsive device, means operative upon de-energization of the restoring member to physically return the traffic responsive device to attracted position, and means, including a front contact of the brake applying device, for completing a temporary energizing circuit for such device, independent of the restoring member and the responsive device.

6. In an automatic train control system, a traffic responsive device, a restoring member therefor, a brake applying device acting when de-energized to produce a brake application, an energizing circuit for brake applying device broken upon de-energization of either the traffic responsive device or the restoring member, an energizing circuit for the restoring member broken upon de-energization of the traffic responsive device, and reset means operable to complete an auxiliary 20 energizing circuit for the restoring member independent of the traffic responsive device.

7. In an automatic train control system, a traffic responsive device normally in attracted position, a restoring member therefor, a brake applying device acting when de-energized to produce a brake application, an energizing circuit for the brake applying device broken upon de-energization of either the traffic responsive device or the restoring member, an energizing circuit for the restoring member broken upon de-energization of the traffic responsive device, means operative upon de-energization of the restoring member to return the traffic responsive device 25 to attracted position, and reset means operable to complete an auxiliary energizing circuit for the restoring member independent of the traffic responsive device.

8. In an automatic train control system, a traffic responsive device normally energized to attracted position, through a tuned circuit, by alternating current, a restoring member therefor normally energized with direct current, a normally energized brake applying device acting when de-energized to pro-

duce a brake application, a normal energizing circuit for the brake applying device broken upon de-energization of either the traffic responsive device or the restoring member, a normal energizing circuit for the restoring member broken upon de-energization of the traffic responsive device, and means operative upon de-energization of the restoring member to return the traffic responsive device to attracted position.

9. In a train control system, a normally energized main relay, a normally energized restoring relay therefor, means operable on release of the main relay to cause the restoring relay to restore the main relay to attracted position, a stick brake applying device initiated upon de-energization of the main relay, acknowledging means to temporarily prevent initiation of the brake applying device, and an acknowledging whistle energized through a circuit including the stick contact of the brake device and a back contact of the main relay.

10. In a train control system, a normally energized main relay, a normally energized restoring relay therefor, means operable on release of the main relay to cause the restoring relay to restore the main relay to attracted position, a stick brake applying device initiated upon de-energization of the main relay, acknowledging means to temporarily prevent initiation of the brake applying device, an acknowledging whistle energized through a circuit including the stick contact of the brake device and a back contact of the main relay, and means causing slow drop away of the restoring relay armature.

11. In a train control system, a main relay, a restoring relay therefor, means operable on release of the main relay to cause the restoring relay to restore the main relay to attracted position, a stick brake applying device initiated upon de-energization of the main relay, acknowledging means to temporarily prevent initiation of the brake applying device by completing a stick energizing circuit for the brake applying device, and an acknowledging whistle energized through a circuit including the stick contact of the brake device and a back contact of the main relay.

12. In a train control system, a normally energized main relay, a normally energized restoring relay, means operable on release of the main relay to cause the restoring relay to restore the main relay to attracted position, a stick brake applying device initiated upon de-energization of the main relay, and also upon de-energization of the restoring relay, reset means for the restoring relay, acknowledging means to temporarily prevent initiation of the brake applying device, and an acknowledging whistle energized through a circuit including the stick contact of the

brake device and a back contact of the main relay.

13. In an automatic train control system, a first relay having an energizing circuit responsive to traffic conditions, a second relay energized through a circuit including a front contact of the first relay, and means, for mechanically moving the armature of the first relay to attracted position, operative upon de-energization of the second relay.

14. In an automatic train control system, a first relay having an energizing circuit responsive to traffic conditions, a second relay energized through a circuit including a front contact of the first relay, means to mechanically move the armature of the first relay to attracted position upon de-energization of the second relay, a stick brake device initiated on de-energization of either of said relays, and a whistle valve energized through a circuit including a back contact of the first relay.

15. In an automatic train control system, a first relay having an energizing circuit responsive to traffic conditions, a second relay energized through a circuit including a front contact of the first relay, means to mechanically move the armature of the first relay to attracted position upon deenergization of the second relay, a stick brake device initiated on de-energization of either of said relays, and a whistle valve energized through a circuit including a back contact of the first relay and the stick contact of the brake device.

16. In an automatic train control system, a first relay having an energizing circuit responsive to traffic conditions, a second relay energized through a circuit including a front contact of the first relay, means to mechanically move the armature of the first relay to attracted position upon de-energization of the second relay, a stick brake device initiated on de-energization of either of said relays, a whistle valve energized through a circuit including a back contact of the first relay and the stick contact of the brake device, and means to cause an appreciable time delay between de-energization of the first relay, and restoring of the first relay armature to attracted position.

50 17. In an automatic train control system, a first relay having a tuned circuit energized with alternating current, a second relay energized with direct current through a circuit including a front contact of the first relay, and means, operative on de-energization of the second relay, for mechanically moving the armature of the first relay to attracted position.

60 18. In an automatic train control system, a first relay having an energizing circuit supplied with alternating current and tuned to oscillate most freely at the frequency of said alternating current, a second relay energized with direct current through a circuit includ- 65 ing a front contact of the first relay, means,

operative on de-energization of the second relay to mechanically move the armature of the first relay to attracted position, and a brake applying device directly initiated by the release of either of said relays.

70 19. In an automatic train control system, a first relay having an energizing circuit supplied with alternating current and tuned to oscillate most freely at the frequency of said alternating current, a second relay energized with direct current through a circuit including a front contact of the first relay, means, operative on de-energization of the second relay to mechanically move the armature of the first relay to attracted position, and a brake applying device initiated by the release of either of said relays.

75 20. In an automatic train control system, a traffic responsive device normally in attracted position, a restoring member therefor, a brake applying device acting when de-energized to produce a brake application, an energizing circuit for the brake applying device broken upon de-energization of either the traffic responsive device or the restoring member, an energizing circuit for the restoring member broken upon de-energization of the traffic responsive device, means operative upon de-energization of the restoring member to restore the traffic responsive device to attracted position, and reset means operable to complete an auxiliary energizing circuit for the restoring member.

80 21. In a train control system, a normally energized main relay, a normally energized restoring relay therefor, means operable on release of the main relay to cause the restoring relay to move the armature of the main relay to attracted position, a brake applying device initiated on deenergization of the main relay, stick means associated with, and making a stick device of, said brake applying device, acknowledging means to temporarily prevent initiation of the brake applying device, and an acknowledging whistle energized through a circuit including a contact on said stick device and a back contact of the main relay.

85 22. In an automatic train control system, a normally energized traffic responsive device, a normally energized restoring member therefor operable when de-energized, to physically restore said device, a normally energized brake applying device acting when de-energized to produce a brake application, and a normal energizing circuit for the brake applying device broken upon de-energization of either the traffic responsive device or the restoring member.

90 In testimony whereof I affix my signature. CHARLES S. BUSHNELL.
